UNITED STATES PATENT OFFICE.

HENRY R. CREWS, OF TOTOWA BOROUGH, NEW JERSEY.

OVERBOX-COVER.

1,384,517.

Specification of Letters Patent.

Patented July 12, 1921.

Application filed April 23, 1921. Serial No. 463,930.

To all whom it may concern:

Be it known that I, HENRY R. CREWS, a citizen of the United States, residing at Totowa Borough, in the county of Passaic 5 and State of New Jersey, have invented certain new and useful Improvements in Overbox-Covers, of which the following is a specification.

This invention relates to concrete and the 10 like over-boxes for burial purposes and particularly to covers for such overboxes. Such a cover should be made strong and it should also be as light as possible, on account of the fact that a simple form of means for handling it at the time of closing the overbox 15 in the grave is required, and it should be adapted for the forming of a good seal all around at that time without the necessity for a workman entering the grave to do the 20 work of sealing; it should further be made with as little vertical dimension as possible so that it can stand edgewise on the overbox until it is to be lowered into closing position thereon and without the grave being widened 25 in order to permit it thus to stand edgewise, resting against the side of the grave. The object of this invention is to provide a cover for a concrete or the like burial overbox which shall be substantially flat (that is 30 without the common arching, which increases the vertical dimension of the cover) and yet both light and also strong enough to permanently carry the weight of the earth filled into the grave above it, and which 35 shall also be adapted to form with the overbox a good seal upon its simply being lowered into covering relation to the overbox and which shall, further, not require any more elaborate means for positioning it in 40 covering relation to the overbox than one or more hooks or hooked bars.

In the drawing,

Figure 1 is a plan view of the metal structure of my cover;

Fig. 2 is a longitudinal sectional view of 45 the cover;

Fig. 3 is an underneath plan of the cover; and

Fig. 4 shows the cover in transverse section and in operative relation to the top of 50 the overbox, which is shown by broken lines.

The metal structure of the cover includes a marginal wall *a* of strip metal the width of which is about equal to the thickness of 55 the finished cover. This strip *a* is bent into oblong form and is made endless, preferably

by having its ends overlapped and riveted together, as at *b*. It should be fairly thick in proportion to its width; that is, if, as is preferable, the strip is $1\frac{3}{4}$ " wide it should be 60 approximately $\frac{1}{4}$ " thick. Having this strip as a marginal wall I provide longitudinal lengths *c* and transverse lengths *d* of strap iron and having bent up their ends and having arranged the lengths *c* parallel to and 65 spaced from each other and the lengths *d* also parallel to and spaced from each other and having interwoven the lengths *c* and *d* after the manner of a basket weave, I secure the several lengths at their bent-up ends *e* 70 to the wall *a*.

The skeleton reinforcement which is formed by these interwoven lengths *c* and *d* is preferably arranged in a horizontal plane somewhat nearer to the plane of the lower 75 edge than the plane of the upper edge of the wall *a*, but not so low but that there will be a space between the bottom of this reinforcement and a groove formed in the bottom of the cover as will be explained. 80

The thus reinforced structure is then laid on a surface which is flat excepting for a raised or upstanding and continuous bead of suitable depth and of somewhat greater width than is represented by the thickness 85 of the side and end walls of the overbox, indicated in Fig. 4 by the character *f*; the overall longitudinal dimensions of this continuous bead and the overall transverse dimension thereof are respectively somewhat 90 less than the inside longitudinal and transverse dimensions of the wall *a*. Further, the bead will have its inner margin continuously beveled. The aforesaid surface and the bead are not shown in the drawings, 95 but it is thought that they will be fully understood in view of the foregoing and on reference to Fig. 4, which shows in cross section the form of the cover that is molded thereon. The wall *a* is placed on said surface in surrounding and parallel relation to the bead; thereupon a concrete plastic mass is filled into the mold formed by said surface and wall, as indicated at *g*, the same being beveled off at its top surface flush with 100 the top edge of the wall *a* and allowed to set hard. The resulting product is a slab of concrete having a marginal metal wall *a* equal in depth to the thickness of the slab and also having the concrete mass therein 105 reinforced by the skeleton frame *c d*. It is of uniform thickness throughout except

ing for the continuous groove *h* formed in the under side thereof by the aforesaid bead, the outer margin of the groove having concrete *i* interposed between it and the wall *a* 5 and the inner margin of the groove being beveled, as at *j*.

When the cover is to be put into use the groove is lined with a layer of pitch or cement in plastic form and the cover then 10 lowered into the grave and made to stand on one of its long sides on the overbox, leaning against the side of the grave. When it is to be lowered into position on the overbox a hook or hooks in the hands of attendants are made to catch on the marginal lip which is left by the groove so as to support it as it is moved from the upright to the horizontal position, and so as to bring the groove, lined with the pitch or cement, 15 into register with the top edge of the overbox; the centering of the cover with reference to the overbox is facilitated by the bevel *j*. Under the weight of the cover the pitch or cement forms a good seal.

20 The cover is light in weight, because it is a relatively thin slab, and it is strong and well adapted to support the superimposed earth because it is reinforced by the wall *a* and skeleton structure *c d*. It is not adapted 25 to be damaged at the margin because of the protecting wall *a*. It can stand in the grave edgewise on the overbox preliminarily to closing without widening the grave or interfering with the introduction of the casket.

30 35 The lip formed by the lower edge of wall *a* and the concrete at *i* affords a hold to the

hooks when lowering the cover into final position, and if the wall should rust away in time the concrete at *i* still will remain to protect the pitch or cement *i* and keep the 40 cover from lateral displacement in the ground.

Having thus fully described my invention, what I claim as new and desire to secure by Letters Patent is:—

45

1. An overbox cover consisting of a flat slab of concrete, a marginal continuous metal well surrounding and bearing all around against the concrete and having its vertical dimension not less than that of said slab, 50 said slab having in its under side a continuous groove parallel with said wall and adapted to receive the upper edge of the overbox, and a reinforcing skeleton frame extending from side to side of said wall and 55 embedded in the concrete, said frame being arranged in a plane nearer the bottom than the top surface of the slab, and the material of the slab intervening between said frame and groove.

60

2. An overbox cover consisting of a flat slab of concrete and a marginal continuous metal wall surrounding and bearing all around against the concrete and having its vertical dimensions not less than that of said slab, 65 said slab having in its under side a continuous groove parallel with said wall and adapted to receive the upper edge of the box, and the material of the slab intervening between said groove and wall all around.

70

In testimony whereof I affix my signature.
HENRY R. CREWS
